UNITED STATES PATENT OFFICE.

BERNHARD F. SCHUBERT, OF WASHINGTON, DISTRICT OF COLUMBIA,
ASSIGNOR OF ONE-HALF TO RUDOLPH SIMMS, OF WASHINGTON,
DISTRICT OF COLUMBIA.

COMBINATION IMPLEMENT.

SPECIFICATION forming part of Letters Patent No. 758,282, dated April 26, 1904.

Application filed June 20, 1903. Serial No. 162,414. (No model.)

To all whom it may concern:

Be it known that I, BERNHARD F. SCHUBERT, a citizen of the United States, residing at Washington, District of Columbia, have invented new and useful Improvements in Combination Implements, of which the following is a specification.

My invention relates to a new and useful combination implement; and its object is to provide a simple and inexpensive device adapted to be used as a cigar holder and cutter and also having the appearance of a pistol. The article is especially adapted for advertising purposes, and suitable advertising matter may be arranged at desired points thereon.

With the above and other objects in view the invention consists in the novel construction and combination of parts hereinafter more fully described and claimed, and illustrated in the accompanying drawings, showing the preferred form of my invention, and in which—

Figure 1 is a side elevation of the device, and Fig. 2 is a section therethrough inverted.

Referring to the figures by numerals of reference, 1 is the bowl of a cigar-holder and is arranged at one end of a stem 2, provided with an enlarged portion 3 adjacent the bowl. A passage 4 extends through the stem to the bowl to permit of the suction of smoke from the bowl. Secured to the enlarged portion 3 in alinement with the bowl is a plate 5, having a circular aperture 6, the edges of which are sharpened. To this plate is hinged a curved lever 7, having a cutting edge 8, which is held normally removed from the aperture 6 by a spring 9.

When the device is in the position shown in Fig. 1, the lever 7 presents the appearance of the trigger of a pistol. By inserting a cigar end into aperture 6 and swinging lever 7 on its pivot said end will be cut, as is obvious. When the article is inverted, as shown in Fig. 2, it can be used as a cigar-holder or a pipe. The device is very simple and inexpensive in construction and affords amusement, as well as being useful and attractive.

In the foregoing description I have shown the preferred form of my invention; but I do not limit myself thereto, as I am aware that modifications may be made therein without departing from the spirit or sacrificing any of the advantages thereof, and I therefore reserve the right to make such changes as fairly fall within the scope of my invention.

Having thus described the invention, what is claimed as new is—

The combination with a pipe comprising a bowl, a stem and an enlarged portion to the stem whereby the pipe simulates a pistol; of an apertured plate embedded and secured within the enlarged portion, a cutting-lever pivoted to the plate, and a spring for controlling the movement thereof, said lever having the appearance of the trigger of a pistol.

In testimony whereof I affix my signature in presence of two witnesses.

BERNHARD F. SCHUBERT.
